UNITED STATES PATENT OFFICE.

JOHN FLETCHER HOLLIDAY, OF LIVERPOOL, AND CHRIS MILLARD ACRES, OF NEW FERRY, ENGLAND, ASSIGNORS TO THE BABCOCK & WILCOX COMPANY, OF BAYONNE, NEW JERSEY, A CORPORATION OF NEW JERSEY.

CHAIN-GRADE-STOKER LINK.

Application filed November 13, 1923. Serial No. 674,450.

To all whom it may concern:

Be it known that we, JOHN FLETCHER HOLLIDAY, of 22 Regina Road, Aintree, Liverpool, England, and CHRIS MILLARD ACRES, of 56 Port Causeway, Bromborough Port, New Ferry, Cheshire, England, subjects of the King of Great Britain, have invented certain new and useful Improvements in Chain-Grate-Stoker Links, of which the following is a specification.

Our invention relates to links for chain grate stokers of the usual type, in which the links are connected by rods passing through openings in the ends of the several links. The usual type of link has a closed eye surrounding the rods, so that when the replacing of such a link becomes necessary, the rods must be withdrawn through adjacent links to free the link to be withdrawn and replaced, and this is a rather difficult operation.

By our invention we provide a link which can be replaced in a chain grate at any point across the grate without disturbing the adjacent links.

Our invention will be best understood from the annexed drawing in which Fig. 1 is a side elevation, partly broken away, showing an illustrative embodiment of our invention; Fig. 2 is a section on the line 2-2 of Fig. 1; Fig. 3 is a section on the line 3-3 of Fig. 1; Fig. 4 is a plan view of the link shown in Fig. 1; Figs. 5 and 6 are side and end views, respectively, of one of the pin-holding members shown in Fig. 1, and Fig. 7 is a fragmentary view in side elevation illustrating a portion of the chain.

Like reference characters indicate like parts in the several views.

In the particular arrangement illustrated, the link 10 has the usual air channels 11 and the distance piece 12. The lower part of the link is provided at either end with a pocket 13 located medial of the cross-section of the link and extending in from the bottom, the sides of the link being thickened to form the walls 14, 14 at either side of the pocket. Through these walls extend pins 15, on each of which is pivoted a member 16 through the hole 17, these members having the shape best shown in Fig. 5, with the center of mass to the right and below the hole 17, as viewed in Fig. 5, so that the member 16 tends to swing by gravity clock-

wise, as viewed in Fig. 5, so that the vertical edges of the coacting members 10 normally tend to separate, and when the link is placed in position on the chain rods, the lower ends of the members are sufficiently separated to permit the notches 21 in the link to pass downwardly over the chain rods 20. As will be noted particularly in Fig. 6, the member 16 is also given a slight taper so that it is thicker at the bottom 18 than at the top 19, the thickness at the bottom being such that that end of the member 16 will have a tight fit between the side walls of the pocket 13 when the member 16 is swung to the dotted line positions shown at the right-hand end of Fig. 1. Each of the members 16 is also provided with a semi-circular recess 20^a, the center of which is in line with the vertical end of the part 18. The upper part 19 of the member 16 is shaped more or less as a horn, so that when the members 16 are swung to their open position, as shown in dotted lines at the right of Fig. 1, so as to move the straight portions far enough apart to permit the chain rod 20 to pass into the notches 21 formed in the side walls 14, these horns will project down into the space finally to be occupied by the rod 20. By pressing on the link, these horns engage with the upper part of the rod and swing the lower portions 18 into the closed position shown in full lines in Fig. 1, thus locking the link on the rod 20. By reason of the fact that the thickness of the part 18 causes a tight fit in the slot 13, the members 16 are restrained from swinging backward on their pivots 15 when the link is on the lower run of the chain sufficiently to permit the links to drop from the chain. In other words, while there may be a limited amount of movement of the member 16, it is insufficient to free them from the chain rod 20.

Similarly, the link may be removed by inserting a chisel between the lower ends of the members 16 and pressing them apart to the dotted line position shown in Fig. 1.

We claim:

1. In a chain grate stoker having links connected by cross rods, a link having a rod notch in each of its end portions and open to the exterior thereof to permit a rod to enter the notch, and a rod-engaging member pivotally supported on the link and having an end portion adapted to extend

beneath the rod in said rod notch, when the member is turned on its pivot.

2. In a chain grate stoker having links connected by cross rods, a link having a rod notch in each of its end portions and open to the exterior thereof to permit a rod to enter the notch, and a rod-engaging member pivotally supported on the link and having an end portion adapted to extend beneath the rod in said rod notch, when the member is turned on its pivot, said member having a surface adapted to engage the link frictionally when the member is turned to move its end portion out of alignment with the rod notch.

3. In a chain grate stoker having links connected by cross rods, a link having a rod notch in each of its end portions and open to the exterior thereof to permit a rod to enter the notch, and a pair of rod-engaging members pivotally supported on the link on opposite sides of the rod notch and each having an end portion adapted to extend beneath the rod in said rod notch when the members are turned on their pivots.

4. In a chain grate stoker having links connected by cross rods, a link having a rod notch in each of its end portions and open to the exterior thereof to permit a rod to enter the notch, and a pair of rod-engaging members pivotally supported on the link on opposite sides of the rod notch and each having an end portion adapted to extend beneath the rod in said rod notch when the members are turned on their pivots, each of said members having a surface adapted to engage the link frictionally when the link member is turned to move its end portion out of alignment with the rod notch.

5. In a chain grate stoker having links connected by cross rods, a link having a medial pocket in each of its end portions and open to the exterior thereof, a rod notch in each of the walls of said pocket and open to the exterior of the link to permit a rod to enter the notch, and a rod-engaging member in said pocket and pivotally connected to the link, said member having an end portion adapted to extend beneath the rod in said rod notch when the member is turned on its pivot.

6. In a chain grate stoker having links connected by cross rods, a link having a medial pocket in each of its end portions and open to the exterior thereof, a rod notch in each of the walls of said pocket and open to the exterior of the link to permit a rod to enter the notch, and a rod-engaging member in said pocket and pivotally connected to the link, said member having an end portion adapted to extend beneath the rod in said rod notch when the member is turned on its pivot, said member having its

said end portion of a thickness to give a tight fit between the walls of said pocket when the member is turned to move said end portion out of alignment with the rod notch.

7. In a chain grate stoker having links connected by cross rods, a link having a medial pocket in each of its end portions and open to the exterior thereof, a rod notch in each of the walls of said pocket and open to the exterior of the link to permit a rod to enter the notch, and a pair of rod-engaging members in said pocket and pivotally supported on the link on opposite sides of the rod notch and each having an end portion adapted to extend beneath the rod in said rod notch when the members are turned on their pivots.

8. In a chain grate stoker having links connected by cross rods, a link having a medial pocket in each of its end portions and open to the exterior thereof, a rod notch in each of the walls of said pocket and open to the exterior of the link to permit a rod to enter the notch, and a pair of rod-engaging members in said pocket and pivotally supported on the link on opposite sides of the rod notch and each having an end portion adapted to extend beneath the rod in said rod notch when the members are turned on their pivots each of said members having its said end portion of a thickness to give a tight fit between the walls of said notch when the member is turned to move said end portion out of alignment with the rod notch.

9. In a chain grate stoker having links connected by cross rods, a link having a medial pocket in each of its end portions and open to the exterior thereof, a rod notch in each of the walls of said pocket and open to the exterior of the link to permit a rod to enter the notch, and a rod-engaging member in said pocket and pivotally connected to the link at one side of said rod notch, said member having a lower end below the pivot adapted to extend beneath the rod in said rod notch when the member is turned on its pivot and having an upper end above the pivot adapted to extend across the rod notch when the member is turned on its pivot to move the lower end of said member out of alignment with the rod notch.

10. In a chain grate stoker having links connected by cross rods, a link having a medial pocket in each of its end portions and open to the exterior thereof, a rod notch in each of the walls of said pocket and open to the exterior of the link to permit a rod to enter the notch, and a rod-engaging member in said pocket and pivotally connected to the link at one side of said rod notch, said member having a lower end below the pivot adapted to ex-

tend beneath the rod in said rod notch when the member is turned on its pivot and having an upper end above the pivot adapted to extend across the rod notch when the member is turned on its pivot to move the lower end of said member out of alignment with the rod notch and said lower end having a thickness to give a tight fit between the walls of said pocket when the member is turned to move said end portion out of alignment with the rod notch.

11. In a chain grate stoker having links connected by cross rods, a link having a medial pocket in each of its end portions and open to the exterior thereof, a rod notch in each of the walls of said pocket and open to the exterior of the link to permit a rod to enter the notch, and a pair of rod-engaging members in said pocket and pivotally connected to the link at opposite sides of said rod notch, each of said members having a lower end below the pivot adapted to extend beneath the rod in said rod notch when the member is turned on its pivot and having an upper end above the pivot adapted to extend across the rod notch when the member is turned on its pivot to move the lower end of said member out of alignment with the rod notch.

12. In a chain grate stoker having links connected by cross rods, a link having a medial pocket in each of its end portions and open to the exterior thereof, a rod notch in each of the walls of said pocket and open to the exterior of the link to permit a rod to enter the notch, and a pair of rod-engaging members in said pocket and pivotally connected to the link at opposite sides of said rod notch, each of said members having a lower end below the pivot adapted to extend beneath the rod in said rod notch when the member is turned on its pivot and having an upper end above the pivot adapted to extend across the rod notch when the member is turned on its pivot to move the lower end of said member out of alignment with the rod notch and said lower end of each of said members having a thickness to give a tight fit between the walls of said pocket when the member is turned to move said end portion out of alignment with the rod notch.
